United States Patent Office

Des. 176,083
Patented Nov. 15, 1955

176,083

WASTE RECEPTACLE

Jean O. Reinecke, Oak Park, Ill., assignor to Federal Tool Corporation, Chicago, Ill., a corporation of Illinois

Application April 11, 1955, Serial No. 35,442

Term of patent 14 years

(Cl. D58—17)

Fig. 1 is a front elevational view of a waste receptacle embodying my new design;

Fig. 2 is a top plan view thereof;

Fig. 3 is a side view of the waste receptacle; and

Fig. 4 is a back view thereof.

I claim:

The ornamental design for a waste receptacle, substantially as shown.
